UNITED STATES PATENT OFFICE.

JOSEPH FOSSA, OF DANVERS, MASSACHUSETTS, ASSIGNOR TO UNITED SHOE MACHINERY CORPORATION, OF PATERSON, NEW JERSEY, A CORPORATION OF NEW JERSEY.

METHOD AND MECHANISM FOR SEWING REVERSE PURL.

1,370,528.

Specification of Letters Patent.

Patented Mar. 8, 1921.

Application filed August 31, 1918. Serial No. 252,249.

To all whom it may concern:
Be it known that I, JOSEPH FOSSA, a citizen of the United States, residing at Danvers, in the county of Essex and State of Massachusetts, have invented certain new and useful Improvements in Methods and Mechanism for Sewing Reverse Purl; and I do hereby declare the following to be a full, clear, and exact description of the invention, such as will enable others skilled in the art to which it appertains to make and use the same.

This invention relates to sewing a reverse purl on buttonhole sewing machines in which the sewing mechanism comprises an upper needle, an under needle, and a looper for taking a loop of upper needle thread and holding it in position below the work for the passage therethrough of the under needle as it carries a loop of under thread to the upper side of the work and into position for the upper needle to pass down therethrough.

As normally operated this type of sewing mechanism sews a seam in which the purl is on the lower edge of the buttonhole slit. By the use of a comparatively light upper thread tension and a heavy under thread tension the purl may be reversed or brought to the upper edge of the buttonhole slit, as is sometimes desirable in doing special work. This heavy tension is objectionable, however, particularly during the spacing of the work. It is accordingly the object of the present invention to provide for sewing a reverse purl without the use of an abnormal under thread tension which will interfere with the ready spacing of the work. To this end the invention contemplates completing the taking up of the upper needle thread to tighten the loop through which the under thread has been passed and then relieving the tension on the upper thread before the looper releases the loop through which the under needle is passing. Sufficient slack thread is thus retained in the latter loop of upper needle thread to reach to the upper side of the work when the under needle returns and tightens the loop of under needle thread. Consequently, the loop of upper needle thread is readily drawn to the upper side of the work by the tightening of the loop of under needle thread without any ab-

normal tension on the under thread. The upper needle thread is preferably thus taken up and released by a take-up acting to take up the thread and to draw thread through the tension for the next stitch while the looper still holds the loop of thread through which the under needle is passing.

The invention will be readily understood from the following detailed description of the construction and mode of operation of the mechanism shown in the accompanying drawings.

In the drawings, Figure 1 is a side elevation showing so much of a buttonhole sewing machine as is necessary to illustrate the application of the present invention thereto; Fig. 2 is a detail view of the take-up and the auxiliary slack thread controlling device; and Figs. 3 and 15 are diagrammatic views illustrating the mode of operation of the thread handling devices in sewing a reverse purl overseam.

In the drawings the invention is shown as applied to the buttonhole sewing machine shown and described in Patent No. 1,063,880, June 3rd, 1913. The sewing mechanism of this machine comprises the upper needle 2, the under needle 4, and the looper 6, which are constructed and operate as fully explained in said patent. The upper needle thread leads from the upper end of the needle bar over an auxiliary slack thread controller 8 which is in the form of a bent wire arranged to be engaged by the thread during the downward stroke of the needle bar. The thread leads from the auxiliary controller through two thread guides 10 to the thread tension device 12. Between the two thread guides 10 the thread is acted upon by a combined take-up and slack thread controller 14 which is carried by the crank on the sewing shaft 16 through which the under needle mechanism is operated. The location of this combined take-up and thread controller and the manner in which it is mounted on the crank corresponds to the location and manner of mounting the slack thread controller shown and described in the above patent. As shown, the take-up and controller comprises a wire frame provided with a horizontal portion 18 which substantially corresponds in its action upon the thread to the slack thread controller of

the patent. The frame is also provided with a vertical thread engaging portion 20 which acts upon the thread between the stationary guides 10 to take up the thread and to draw 5 thread through the tension for the next stitch, this part being timed to act on the thread while the looper still retains a loop of thread below the work. The lower end of the take-up part of the wire frame is so 10 located that it passes from engagement with and releases the thread just before the looper releases the loop of thread below the work.

The mode of operation in sewing the seam is illustrated diagrammatically in Figs. 3 15 to 14. Assuming that the cycle begins with the parts in the position indicated in Figs. 3 and 6, in which the under needle is in its retracted position, the looper is holding a loop of upper needle thread in position 20 for the passage therethrough of the under needle, the upper needle is nearly at the limit of its upward stroke, and the take-up is in the position indicated in Fig. 1. The mode of operation is as follows: The 25 under needle moves upward into the position indicated in Fig. 4, and during this movement the upper needle completes its upward movement. The take-up moves from the position of Fig. 1 to the position of Fig. 30 4, and tightens the loop 22 of the preceding loop of upper needle thread, while the looper continues to hold the loop 24 through which the under needle is passing. Up to this time slack thread has been retained in the loop 35 22 so that this loop has been long enough to reach to the upper side of the work, as will presently appear. The purl formed by the interlacing of the under loop of upper needle thread with the under needle thread is therefore 40 readily drawn to the upper side of the work by a comparatively light pull on the under needle thread, as will also appear. While the looper is still holding the loop 24 the take-up 20 completes its taking-up action 45 and the thread passes from the lower end of the take-up and into the opening above the slack thread controller 18, thus relieving the tension on the upper needle thread before the loop 24 is released by 50 the looper. This loop remains slack while the upper needle passes down through the loop of under thread, as indicated in Figs. 9 and 10, and while the looper takes the loop 55 26 of upper needle thread and carries it into position above the under needle which has meanwhile been retracted to its lower position, the upper needle also returning to the position of Figs. 3 and 11. As the under needle completes its backward stroke it 60 tightens the loop 28 of under needle thread and thereby draws a bight of the loop 24 of the upper needle thread to the upper side of the work. The loop 24 in Figs. 11 and 14 now corresponds to the loop 22 of Figs. 3 65 and 6, the cycle having been completed.

This loop 24 is tightened by the action of the take-up while the loop 26 is retained by the looper, and while the under needle is passing the succeeding loop of under needle thread up through the loop 26, the take-up 70 acting to relieve the tension on the thread before the looper releases the loop 26, so that this loop in turn remains slack and of sufficient length to be drawn to the upper side of the work by the pull on the under needle 75 thread as this needle again reaches its reTRACTING position.

After the take-up has acted and released the tension on the thread, as above described, the thread controller 18 acts on the 80 thread to control the slack thread above the work so that the needle during its downward stroke will not throw out a loop of thread between its eye and the upper side of the work of sufficient size to interfere with 85 the proper operation of the sewing mechanism. To increase the amount of thread which draws back through the eye of the needle as the needle descends, the auxiliary slack thread controller 8 is provided, and 90 this controller is so shaped as to properly supplement the action of the controller 18 in drawing back the proper amount of thread through the eye of the upper needle.

While it is preferred to connect the take-up with the slack thread controller in applying the invention to the machine of the above patent, in view of the simplicity of the resulting construction it will be understood that the thread may be taken up 100 and the tension on the thread released at the proper times in the sewing cycle by any suitable construction and arrangement of take-up, and that the take-up may be operated by any suitable mechanism. 105

What is claimed is:

1. A method of sewing a reverse purl overseam which consists in passing a loop of upper thread down through a loop of under thread and then through the work 110 and retaining it below the work, passing a loop of under thread up through the loop of upper thread to a position above the work for the passage down therethrough of the succeeding loop of upper thread, and retaining sufficient slack in the loop of thread below the work to reach to the upper side of the work until after the under thread loop passing therethrough has been tightened and the subsequent loop of under 115 thread has been carried to the upper side of the work. 120

2. A method of sewing a reverse purl overseam which consists in passing a loop of upper thread down through a loop of under thread and then through the work, holding the loop below the work, passing a succeeding loop of under thread up therethrough, taking up the upper thread to 125 tighten the preceding loop, and then reliev-

ing the tension on the thread while maintaining the held loop of sufficient length to reach to the upper side of the work.

3. A mechanism for sewing a reverse purl 5 overseam comprising an upper needle, an under needle, a looper for taking a loop of upper thread and holding it below the work for the passage up therethrough of the under needle, a take-up, and means for actuating the take-up to complete the taking up 10 and release of the upper thread while the looper is holding a loop of said thread below the work.

4. A mechanism for sewing a reverse purl 15 overseam comprising an upper needle for carrying a loop of thread down through the work, an under needle for carrying a loop of another thread up through the loop of upper thread into position above the work 20 for the passage of the upper needle therethrough, and means for maintaining the loop of upper thread below the work sufficiently long to reach to the upper side of the work until the loop passed therethrough by 25 the under needle is tightened by the retraction of the under needle.

5. A mechanism for sewing an overseam, a reciprocating upper needle bar, an under needle, a looper for taking a loop of thread 30 from a needle carried by the upper needle bar to the upper end of which the thread leads and holding it in position for the passage therethrough of the under needle,

and a thread controller adjacent to the upper end of the needle bar having a thread 35 deflecting surface along which the thread is carried by the downward movement of the needle bar.

6. A mechanism for sewing a reverse purl 40 overseam comprising an upper needle, an under needle, a looper for taking a loop of upper thread and holding it below the work for the passage up therethrough of the under needle, a combined take-up and thread controller, and means for actuating the 45 same to take up and release the upper needle thread while the loop is retained by the looper, and to thereafter control the thread during the downward stroke of the upper needle. 50

7. A buttonhole sewing machine, having, in combination, an upper needle for carrying a loop of thread down through the work, an under needle for carrying a loop of thread up through the buttonhole slit into 55 position above the work for the passage of the upper needle down therethrough, a looper for taking a loop of upper needle thread and holding it below the work for the passage up therethrough of the under 60 needle, a takeup, and means for actuating the takeup to complete the taking up and release of the upper needle thread while the looper is still holding a loop of said thread below the work. 55

JOSEPH FOSSA.
